UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed May 26, 1920. Serial No. 384,351.

This invention relates to hydrocarbon motors, and particularly to combustion heaters therefor.

The principal object of the invention is to provide a combustion heater adapted to operate independently of the throttle in establishing a flow of mixture to the heater and effecting the ignition thereof.

Another object of the invention is to provide a simple and efficient construction which shall dispense with the use of an auxiliary carburetor for supplying the mixture to the combustion heater.

Another object of the invention is to provide a combustion heater operating independently of the throttle which may be embodied in a self-contained structure and which may be inserted directly in the intake manifold or conduit, and, therefore, may be easily and economically applied to manifolds of widely varying types.

Another object of the invention is to provide, in a construction having the above objects in view, means for cutting off the supply of mixture to the combustion heater when the throttle is opened to a predetermined extent.

With these objects and others in view, the invention is embodied in preferable form in the construction and arrangement herein-after described and illustrated in the accompanying drawings, in which—

Figure 1 is a side elevation partly in vertical section of the mixture forming and feeding system of a hydrocarbon motor containing my improvements in one form thereof;

Figure 2 an enlarged detail longitudinal section of the combustion heater and draft inducing means in the intake conduit;

Figure 3 a detail end elevation of the combustion heater structure shown in Figure 1;

Figure 4 a view similar to Figure 1 of a modified form of the invention; and

Figure 5 still another view of the same character illustrating a possible application of cut-off means for the combustion heater, interconnected with the throttle.

Referring to the drawings, 10 indicates a carburetor, which may be of any unusual construction, and 11 an intake manifold, pipe or conduit leading from said carburetor to the hydrocarbon motor 12. Mounted in the vertical section of said intake conduit above the carburetor is a throttle valve 13

of the ordinary butterfly type. According to the illustration in Figure 1, the device is adapted to be mounted in the vertical section of the intake conduit. To this end, a portion of the ordinary conduit pipe is removed and is replaced by a pipe section or shell 14, which is bolted or otherwise secured at its opposite ends to adjoining portions of the intake pipe. Within this member 14 is adapted to be mounted a venturi 15 which is provided with a series of holes 16 therethrough near its entrance end in the line of direction of the flow of the mixture. These holes communicate with an annular recess 17 formed between the outer portion of the venturi and the wall of the section 14 and this annular recess communicates by a port 18 with a longitudinally extending passageway 19 formed in an enlarged portion of the member 14. This passageway is closed at its farther end by means of a plug 20 and a channel 21 leads from the passageway to a smaller restricted passageway 22 which is offset from the center of the passageway 21 and which in turn communicates with a mixture receiving chamber 23 formed in a removable plug 24 which may be made of any suitable heat resisting material. This plug is adapted to be held in position within the enlarged body portion of the pipe section by means of a dowel pin 25 entering a recess 26 in the plug. The upper or rearward end of the chamber formed in this plug is adapted to be closed by a window 27 formed of glass or other transparent material and the edges of which are clamped between gaskets 28 and 29, against the latter of which gaskets bears a threaded washer or retaining plug 30.

This glass member not only constitutes a closure for the end of the chamber 23 so as to prevent the escape of mixture therefrom, but also provides an observation window through which the combustion chamber may be inspected and the ignition of the mixture observed.

The chamber 23 receives the mixture in a finely sprayed condition owing to the offset arrangement of the small passageway 22. From the chamber 23 the spray passes through a screen 31 held between a washer 32 and a gasket 33, whereby the mixture is still more finely atomized. This finely divided mixture then enters a combustion chamber 34 in which is located a spark plug 35 constituting ignition means for the ex-

ulsive mixture. From the combustion chamber where the mixture is ignited, the gases are drawn through a port 36 into a space 37 annularly surrounding the venturi. 5 Apertures 38 are formed in the venturi at the most restricted portion thereof and establish communication between the said recess 37 and the interior of the venturi, whereby a strong suction is exerted upon the outlet 10 of the passageway leading through the combustion chamber so as to induce a draft of the explosive mixture from the intake conduit, through the inlet of the combustion heater passageway and into the combustion 15 chamber, and thence out again into the intake conduit. The burned gases mix with the main supply of mixture coming from the carburetor, and raise the temperature of the latter sufficiently to vaporize it to a completely combustible mixture.

It will be seen that a combustion heater is provided which is independent of the throttle in operation, which requires no moving parts and which may be embodied in a single 25 structure consisting of a short pipe section having an enlarged body sufficient to permit of the formation therein of a by-pass and a combustion chamber, which structure may be readily placed in the manifold line with 30 very slight change in the existing construction of the latter.

It is clear that other means than the Venturi tube may be provided in the intake conduit in order to create a suction in the 35 passageway leading through the combustion chamber. For instance, another form of such means of restriction is illustrated in Figure 4. In the arrangement shown in this figure, 40 indicates the carburetor, 41 the 40 vertical outlet section of the intake conduit, 42 the throttle valve, 43 a horizontal section of the intake conduit, and 44, a part of a hydrocarbon motor to which the intake conduit leads. On this horizontal section of the 45 conduit is mounted a by-pass pipe 45 having both its inlet end 46 and its outlet end 47 communicating with the intake conduit at points between the main throttle and the motor. 48 constitutes the restriction means 50 for the intake conduit adapted to create a suction through the by-pass pipe, this restriction means being located adjacent to the outlet and a short distance in front of the same, toward the throttle, and consisting of a hand-operated screw plug valve 49. The outlet end of the by-pass pipe projects longitudinally for some distance into the intake conduit in the direction of the motor, thus probably obtaining to some extent a slight 60 aspirating or injector effect upon the passageway through the combustion chamber.

With a combustion heater of the type shown in Figures 1 to 4 inclusive, it is evident that the supply of the mixture to the combustion chamber will increase as the suc-

tion through the intake conduit is increased and as the throttle is opened more widely, and that hence the heat supplied to the intake conduit will be increased in proportion to the extent of throttle opening. This operation and the condition of temperature in the intake arising therefrom may prove to be desirable in connection with the use of kerosene or other fuels heavier than gasoline in the motor. When more volatile fuels are used, however, it may be desirable to render the combustion heater inoperative after the motor has become warmed up so that the supply of heat to the main mixture passage of the intake conduit will be cut off, thus avoiding loss of volumetric efficiency due to excessive expansion. In Figure 5 there is illustrated a construction adapted to accomplish this end, and in this arrangement only a small section of the intake manifold is shown. 50 indicates the intake conduit, 51 a by-pass pipe having both inlet and outlet ends communicating with the intake conduit and providing a passageway for explosive mixture through a combustion chamber 52 in which is mounted an ignition spark plug 53. A venturi 54 is mounted in the intake conduit and serves to establish a suction upon the outlet end of the passageway through the heater. The inlet end of the by-pass pipe communicates with a hollow boss 55 formed or attached to the outside of the intake conduit pipe. In this chamber is adapted to be mounted a valve 56, preferably of the butterfly type, and operable by means of a link 57 connected to an arm 58 projecting from the pivot of the main throttle 59 which is mounted in the intake conduit. The connection between the two valves is such that when the main throttle is moved away from its closed position, the valve in the by-pass will be moved toward its closing position, and when the throttle has been moved to substantially fully open position, the valve in the by-pass will be closed, thus cutting off the supply of explosive mixture to the combustion chamber and rendering the combustion heater inoperative. When the throttle is closed or is set at idling position, the combustion heater valve will be correspondingly opened so as to permit heat to be again supplied to the intake conduit.

Having thus described my invention, what I claim and desire to secure by Letters Patent is:

1. In combination with a hydrocarbon motor, means for forming an explosive mixture, a conduit leading from said means to the motor, a throttle, a combustion heater, a mixture passageway leading through said combustion heater, and means in said conduit independent of the throttle for producing the passage of mixture through said passageway and heater.
2. In combination with a hydrocarbon

- motor, means for forming an explosive mixture, a conduit leading from said means to said motor, a throttle, a combustion heater, a mixture passageway leading through the heater, and means in the conduit between the throttle and motor for establishing a suction from the engine through said passageway.
3. In combination with a hydrocarbon motor, means for forming an explosive mixture, an intake conduit leading from said means to the motor, a throttle, a combustion heater having a mixture inlet and an outlet, both communicating with the intake conduit between the throttle and the motor, and means to effect the passage of mixture through said combustion heater.
4. In combination with a hydrocarbon motor, means for forming an explosive mixture, an intake conduit leading from said means to the motor, a throttle, a by-pass communicating at both ends with said intake conduit with both its inlet and outlet between the throttle and said motor, a combustion heater in said by-pass, and means to induce a suction through the by-pass to draw a part of the mixture therethrough.
5. In combination with a hydrocarbon motor, means for forming an explosive mixture, an intake conduit, a throttle, a combustion heater, a passageway in which said heater is located communicating both at its inlet and outlet with said conduit between the throttle and motor, and means to restrict said conduit to effect a suction through said passageway.
6. In combination with a hydrocarbon motor, means for forming an explosive mixture, a throttle, an intake conduit leading from said means to the motor, and a removable section adapted to be inserted in the conduit between the throttle and motor, and including therein a passageway forming a continuation of the conduit, means for locally restricting said passageway, a by-pass having suction through the same induced by said restriction, and a spark plug in said by-pass for igniting mixture.
7. In combination with a hydrocarbon motor, means for forming an explosive mixture, an intake conduit, a throttle, a combustion heater receiving mixture from the intake between the throttle and motor and delivering the burned mixture to said intake, and means for rendering the heater inoperative upon the opening of the throttle to a predetermined extent.
8. In combination with a hydrocarbon motor, means for forming an explosive mixture, an intake conduit, a throttle, a combustion heater, means independent of the throttle for effecting a supply of mixture to the heater, and a valve for the heater connected to the throttle and operable to move to closing position as the throttle is opened.
9. The combination with a hydrocarbon motor having an intake conduit, and a throttle valve in the intake conduit, of a combustion heater having both its inlet and outlet connected to the conduit on one side of said throttle, and variable restriction means in the conduit between said inlet and outlet.
10. The combination with a hydrocarbon motor having an intake conduit, and a throttle valve in the intake conduit, of a combustion heater having both its inlet and outlet connected to the conduit on one side of the throttle, and valve means in the conduit between said inlet and outlet.
11. A regenerator for an internal combustion engine comprising a casing adapted to envelope the intake manifold of an engine and provided with a torch nozzle directed toward the manifold within the casing, an ignition chamber mounted on the casing for which the torch nozzle is an outlet and provided with an expansion fuel inlet, and ignition means in the chamber for firing the fuel passing therethrough.
- In testimony whereof I affix my signature.

LIONEL M. WOOLSON.
